UNITED STATES PATENT OFFICE.

ISAAC P. TURNER, OF TROY, ASSIGNOR TO JAMES K. P. PINE, OF LANSINGBURG, NEW YORK.

CUFF-BOX.

SPECIFICATION forming part of Letters Patent No. 295,958, dated April 1, 1884.

Application filed August 26, 1881. (No model.)

To all whom it may concern:

Be it known that I, ISAAC P. TURNER, of the city of Troy, county of Rensselaer, and State of New York, have invented a new and 5 useful Improvement in Cuff-Boxes, of which the following is a specification.

This invention, which relates to the novel construction of a cuff-box, has for its object to furnish an inclosure by which the cuffs may 10 be securely packed therein for shipment, and which, when opened, may be used to display the cuffs to advantage.

My invention consists in constructing and combining a box-cover and tray so as to form 15 a cuff-box, with the cover constructed to have a greater depth than the tray, and being contracted on its inner side and nearest its enclosed top by an additional thickness of board, so that the edge of the latter will support the 20 tray and form a seat for it, and thus constructed the cover may be turned over and the tray and cuffs placed in the cover for displaying the cuffs, and when to be packed for shipment the tray and cuffs are taken from the cover, 25 and the latter passed down over them. By this means of construction, when cuff-boxes are opened and placed in show windows and cases for display, the two parts of box are necessarily kept together in one place without loss of room, and are easily put together for 30 transportation.

In the accompanying drawings there are four illustrations designating my invention and its parts, like letters indicating like parts 35 in all of the figures.

Figure 1 illustrates in perspective the cuff-box with the cover placed over the cuff-tray and as arranged for transportation. Fig. 2 represents in perspective the cover removed 40 from the tray and turned over, illustrating the manner of forming a stop or rest for the cuff-tray within the interior of the cover by means of a thickness of card-board placed on the inner side of the cover nearest its closed top, 45 and at a distance from the open bottom of the cover equal to the depth of the tray. Fig. 3 illustrates in perspective the cuff-tray inserted in the upturned cover and as arranged for displaying the cuffs placed in the tray, the 50 latter being prevented from settling down in the cover by means of the stop or rest shown in Fig. 2. Fig. 4 illustrates in perspective the cuff-tray as removed and separated from the cover.

The several parts of the cuff-box thus illustrated are designated by letters of reference, and their connected combination described as follows:

The letter B denotes the cover, which is made larger than the tray C, to receive the latter 60 and to pass over it, and the cover B is also made deeper than the tray C, so as to inclose the cuffs, which, when placed in the tray, will project upwardly beyond the partition and upper edges of the tray.

Upon the inner side of the cover B, and at a distance from its open bottom equal to the depth of the tray C, there is made the stop or rest S, formed by means of a thickness of card-board attached to the inner side of the cover 70 at the point designated, with sufficient distance between this stop S and the top of the cover B to leave room for that portion of the cuffs which projects above the edge of the tray when placed therein. The stop S arrests the 75 descent of the cuff-tray when inserted in the cover, as shown in Fig. 3, and keeps the tray in place when the cover is placed over the tray, as shown in Fig. 1. The tray C is divided into two compartments, A A, by means of the partition P, into which compartments the cuffs are placed. As curled up, the cuffs project above the edge of the cuff-tray C when placed 80 in the compartments, and so as to be visible and easily seen, when the cuff-tray is inserted in the inverted cover, as shown in Fig. 85 3, and the cuff tray and cover by their construction as thus made are kept together.

The letters N N designate two recesses cut from the lower edge of the cover, to grasp the 90 tray when it is desired to remove the former.

Having thus described my invention, what I claim, and desire to secure by Letters Patent, is—

As a new article of manufacture, a cuff-box 95 composed of the cover B, having the side recesses, N, and stop S at a distance from its open bottom equal to the depth of the tray, and the tray C, of less vertical depth than the cover, the tray being adapted to be inserted 100 in the cover inverted for displaying the cuffs placed therein above the edge of the tray, as shown and described.

ISAAC P. TURNER.
